UNITED STATES PATENT OFFICE

FREDERICK LLEWELLYN, OF SHARON, PENNSYLVANIA, ASSIGNOR TO WESTINGHOUSE ELECTRIC & MANUFACTURING COMPANY, A CORPORATION OF PENNSYLVANIA

TANK STRUCTURE

Application filed November 5, 1930. Serial No. 493,485.

My invention relates to electrical apparatus and more particularly to the tank structure of encased oil-immersed electrical apparatus, such as transformers of very large size and capacity.

During recent years, the size of oil-immersed transformers has so increased, that it has become customary in transformers of large size to split the tank into two sections for transportation or handling, the tank being sectionalized at such an elevation that the transformer could be shipped in the lower section thereof. Previously the same cover used in the general assembly of the transformer was used during shipment of the lower section of the split tank. This necessitated the removal of the fittings attached to the top of the transformer, the plugging of the openings left by the fittings and the unfastening of the cover from the casing. The assembly of the tank at its destination required the reverse order of the work just mentioned.

In the final assembly of the tank, gas leakage is one of the difficulties encountered when the cover is secured by bolts. As the size of transformers increases, the work necessary for detaching the transformer fitting from the tank, for shipment becomes involved and entails considerable time and expense. Sectionalizing the tank for shipment often reduces the freight charges, which are sometimes based on the volume of the unit shipped.

The general object of my invention is to improve the structure of a sectionalized tank.

A further object of my invention is to provide a sectionalized transformer tank which shall be free from leakage and economical to construct.

Another object of my invention is to provide a transformer tank or casing which may be conveniently and economically disassembled for shipment and reassembled thereafter.

A further object is to eliminate, and, consequently, to save the cost of, an angle ring, drilling both the angle ring and cover plate, bolts nuts and gasket.

In accordance with my invention, the upper end of the sectionalized tank section is closed by a cover plate, which is secured thereto by welding while a temporary cover closes the lower section of the split tank during shipment.

The invention, together with additional objects and advantages thereof, will be better understood from the following description of a specific embodiment, when read in conjunction with the accompanying drawing in which:

Figure 1 is a view, partly in front elevation and partly in section, showing an encased oil-immersed transformer embodying my invention;

Figure 2 is an enlarged vertical sectional view showing the top portion of the split tank.

Figure 3 is a sectional view showing the lower section of the transformer tank closed by a temporary cover and ready for shipment or handling.

Like reference characters indicate similar parts in the different figures of the drawing.

Referring specifically to the drawing, the apparatus shown in Fig. 1 comprises a tank 1 containing an oil-immersed transformer 2, enclosed by a suitable casing 3. Radiators 4 and headers 5 of suitable construction may be attached to the casing 3. As is usual in oil-immersed transformers, there is sufficient space between the transformer 2 and the cover 6 to contain the oil necessary for the cooling of the transformer, the transformer leads, bushings and connections (not shown). The upper portion 7 of the tank is separable from the lower portion thereof, as shown in Figs. 1 and 2.

Secured around the lower edge of the upper section 7 is an angle ring 8 which provides a laterally extending flange. The flange of the angle ring is provided with bolt holes 9 suitably spaced for receiving connecting bolts 10. Ribs 12 are attached to upper section 7 by suitable means, while a cover 6 is firmly secured, for example, by a weld 13 to ribs 12 and the upper section 7. The ribs 12 strengthen the union of the cover 6 and the upper section 7 and provide a rest for the cover 6. The

weld 13 serves also as a seal, thereby eliminating the usual gasket between the cover and the tank.

As shown in Figs. 1 and 3, an angle ring 5 14 is secured around the upper edge of the lower portion of the casing 3 at its meeting edge 16 in any suitable manner and provides a laterally extending flange which is provided with bolt holes 17 of the same size and spacing as those of angle ring 8 of the upper section 7. A temporary cover 18 is provided for use during shipment and storage that engages the flange 14 and is locked thereto by means of bolts 10, as shown in Fig. 3. A 15 solid temporary cover 18 is used, thus eliminating the apertures in the original cover after the usual transformer fittings have been removed.

Upon arrival at its destination, the temporary cover 18 is removed from the casing 3, and the upper section 7, with all parts attached to the cover, as before shipment, is replaced.

It will be seen, therefore, that I have provided a transformer-tank structure, so divided into upper and lower parts that the transformer may be shipped in the lower part, immersed in oil, and the cover and upper section may be shipped with all parts attached 25 to the cover, assembled, thereby reducing the height and volume of the units to be transported and also eliminating the inconveniences and expense involved in disassembling the fittings, leads and connections from the 30 cover of the tank, and covering the openings thereby exposed.

Although I have shown and described certain specific embodiments of my invention, I am fully aware that many modifications 40 thereof are possible. My invention, therefore, is not to be restricted except insofar as is necessitated by the prior art and by the spirit of the appended claims.

I claim as my invention:

45 1. In combination, a transformer having an enclosing split casing, a fixed cover welded to the upper edge of said casing, a temporary cover, and means for attaching said temporary cover to the split edge of said enclosing 50 split casing.

2. In combination, a transformer having an enclosing casing, said enclosing casing being divided into an upper section and a lower section, a fixed cover welded to the upper edge 55 of said upper section, a temporary cover, and means for attaching said temporary cover to said lower section.

3. In combination, a transformer having an enclosing casing, said enclosing casing being divided into an upper section and a lower section, a fixed cover welded to the upper edge of 60 said upper section, a series of rib braces around the inside top edge of said upper section, means for securing said rib braces to 65 said upper section, a temporary cover, and

means for attaching said temporary cover to said lower section of said enclosed casing.

4. In combination, a transformer having an enclosing casing, said casing being divided into an upper section and a lower section, a series of rib braces secured around the inside top edge of said upper section, and means for securing said series of rib braces to said upper section, a fixed cover welded to the upper edge of said upper section of said casing and 70 welded to said series of rib braces, a temporary cover, and means for attaching said temporary cover to the lower section of the said casing.

In testimony whereof, I have hereunto subscribed my name this 29th day of October, 1930.

FREDRICK LLEWELLYN.
